SHIPPING CONTAINER

John Lawler and William I. Kavin, San Francisco, Calif., assignors to Poultry Producers of Central California, San Francisco, Calif., a corporation of California

Application October 31, 1932, Serial No. 640,453

9 Claims. (Cl. 217—12)

The invention relates to containers and particularly to a shipping crate or box.

One of the objects of the invention is the provision of a shipping crate or box which may be repeatedly returned for filling and shipping.

Another object of the invention is the provision of a shipping crate having two demountable walls, interchangeable as to their respective positions, to facilitate the assembling and closing of the crate.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawing:

Figure 1 is a perspective view of the crate of our invention as it appears when closed.

Figure 2 is an end elevation of the crate a portion being broken away to show the arrangement of the parts.

Figure 3 is a fragmental view partly in section and partly in elevation showing the stud member of the locking means.

Broadly, the shipping crate or box of my invention comprises end walls to which adjacent side walls are permanently secured so that a rigid foundation structure is provided. The other adjacent side walls are each demountably secured to the end walls with one lapping the edge of the other. Interposed between the demountable side walls and the end walls are means operable to release the side walls by lateral movement thereof. To guard against accidental lateral movement of the lapping demountable wall, a manually operated catch is provided which normally holds the wall in operative position. The demountable sides are identical so that they may be interchanged thus enabling a packer to close or assemble the crate quickly without the need of selecting individual walls; and because of the securing means provided, no other fastening is required.

In greater detail, the shipping crate of our invention is preferably made of wood; and comprises end walls 2, reinforced with cleats 3, as is the usual practice in box construction. The height of the ends, as shown in Figure 1, is preferably greater than their width by two thicknesses of the material used in the side walls, in order to bring the various parts of the crate into interlocking relation without undesirable spaces. Fixedly secured to the bottom edges of the end walls is the bottom wall of the crate. The bottom is made of closely spaced slats 4, which extend beyond the lower corners of the end walls a distance approximately equal to the thickness of the stock used, so as to

form ledges 6, on which the front and back of the crate may rest.

An adjacent side wall 7 is fixedly secured to the rear edges of the end walls, and forms the back of the finished crate. The construction of this wall is the same as the bottom wall except that the outer longitudinal edges of the slats do not extend beyond the edges of the end walls, but rest on the ledge 6 along the bottom edge, and lie flush with the end walls along the top edge.

Encircling each end wall and connected bottom and rear walls is a metallic reinforcing band or strip 8, which is secured by nails at suitable intervals to the exposed (upper and front) edges of the end wall, and overlying the rear and bottom walls, as shown. The strip thus serves not only to bind the bottom and rear edges of the crate and reinforce the fastening of the bottom and rear walls to the ends, but on the exposed upper and front edges of the ends, the strip provides a secure mounting for fastening means wherewith to attach the demountable walls. At spaced intervals along the exposed edges of the end walls headed studs 9 are arranged on the strip 8 in any suitable manner, preferably by riveting as shown in Figure 3. Preferably two such studs are disposed in the strip on each upper and front edge of each end wall.

To give greater rigidity to the structure and to prevent shifting of the contents, a central partition 11 similar to the end walls is provided; and the walls 4 and 7 are also secured to it. Thus a crate of substantial structure, having two divisions with open top and front is presented.

The remaining walls comprising the front and top of the crate generally designated in Figure 2 as 12 and 13 respectively, are identical in structure and size, so that they may be demounted and interchanged indiscriminately. Each of these sides is made preferably of a wire central slat 16 and two narrow margin slats 17, secured at their ends by a cleat 18 with wide spaces between the slats.

Extending across the ends of the inner surface of each of the demountable sides or walls is a metallic band or strip 21, the ends 22 of which are turned up at right angles against the outer edges of the margin slat to protect the wood.

Slots 23, each aligned with a stud 9, are provided in the portions of the strip which extend across the spaces between the slats. These slots are shaped and proportioned to pass the head of the stud 9 at the end remote from the corner between the two demountable sides, and to engage the neck of the stud at the other end.

It will be noted that the width of each of the demountable sides 12 and 13, is equal to the heights of the end walls 2. The placing of the

front wall 12 is accomplished by passing the heads of the studs 9 through the slots 23 and then dropping the side or moving it laterally to bear against the shoulder 6 at the bottom, at which time the 5 narrow portions of the slots are engaging the necks of the studs under the heads, so that the side wall is held firmly in place. The upper edge of the front wall then lies flush with the upper edge of the end wall.

10 The top wall 16 is similarly applied and when in position extends beyond or overlaps both the fixed back wall and the demountable front wall, which thus cannot be disengaged until the top is removed.

15 In the specification and claims the term "lateral movement" is used to designate a sliding movement in the same plane in which the demountable side lies when in position on the crate, to effect the removal or application of the side.

20 Accidental lateral releasing movement of the top is prevented by a manually operated catch of any suitable character such as the upwardly curved spring 24 mounted on the partition 11. The free end of the spring is preferably bent downwardly into a notch 26 in the edge of the partition, leaving a shoulder 27 which extends above the surface of the partition.

As the top is moved transversely to engage the studs, the spring flattens out against the partition 30 to let the margin slat pass. The parts are proportioned so that when the studs have been seated, the spring snaps up back of the margin slat 17, as best shown in Figure 2; and thus prevents backward transverse movement to disengage the studs. 35 The top cannot be moved until the spring catch has been manually depressed, so that the engaged slat can be moved transversely over it.

The shipping crate of our invention is designed chiefly for use in local trade to convey eggs, 40 poultry and other products from the producer to the wholesaler or distributing center. Its use is practical only if the cost of transportation for short hauls permits. When the empty crates are being returned, considerable space can be 45 served if two open crates are nested together and the four demountable sides laid on top.

We claim:

1. A container comprising end walls; adjacent side walls permanently secured to the end walls; 50 adjacent side walls demountably secured to the end walls, one lapping the edge of the other; means securing each demountable wall to the end walls and operable to release the demountable wall by lateral movement in the plane thereof, and a manually releasable catch for preventing lateral movement of the lapping side wall.

2. A container comprising end walls; adjacent side walls permanently secured to the end walls; 60 adjacent side walls demountably secured to the end walls, one lapping the edge of the other; studs fixed in the end walls, means arranged on the demountable walls for slidably engaging the studs, and a manually releasable spring catch 65 for preventing lateral movement of the lapping side wall.

3. A container comprising end walls; adjacent side walls permanently secured to the end walls; adjacent side walls demountably secured to the 70 end walls, one lapping the edge of the other and preventing movement thereof; a metallic strip disposed on the edges of the end walls below the demountable walls, interlockable means ar-

80 ranged on the strip and demountable walls and releasable by lateral movement of the walls in the respective planes thereof, and a manually releasable spring catch for preventing lateral movement of the lapping side wall.

4. A container comprising end walls; adjacent side walls fixed to the end walls; adjacent side walls demountably secured to the end walls, one lapping the edge of the other; a metallic reinforcing strip disposed about the edges of the end walls over the fixed side walls and below the demountable walls, metallic strips on the ends of the demountable walls, interlocking means disposed on the strips to secure the demountable walls in place and releasable by lateral movement of the demountable walls, and a manually releasable catch for preventing lateral movement of the lapping side wall.

5. A container comprising end walls; adjacent side walls fixed to the end walls; adjacent side walls demountably secured to the end walls, a metallic reinforcing strip disposed about the edges of the end walls over the fixed side walls and below the demountable walls, metallic strips on the ends of the demountable walls, and releasable interlocking means disposed on the strips to secure the demountable walls in place.

6. A container comprising oblong rectangular end walls, two adjacent side walls permanently secured to the end walls, two demountable adjacent side walls interchangeable with respect to each other, and means interposed between the end walls and the demountable walls for removably securing the demountable walls in assembled position.

7. A container comprising oblong rectangular end walls, two adjacent side walls permanently secured to the end walls, two demountable adjacent side walls interchangeable with respect to each other and the edge of one of the permanently secured walls, and one lapping the edge of the other, means securing each demountable wall to the end walls and operable to release the demountable wall by lateral movement in the plane thereof, and a manually releasable spring catch for preventing lateral movement of the lapping side wall.

8. A container comprising a wall, a second wall removably positioned adjacent said first wall, means for locking said walls together and releasable upon lateral movement of said second wall in the plane thereof, a third wall removably positioned adjacent the first wall and overlapping the second wall to hold the latter against lateral movement, and means for locking the third and 130 first walls together and releasable only upon lateral movement of said third wall in the plane thereof.

9. A container comprising a wall, a second wall removably positioned adjacent said first wall, 135 means for locking said walls together and releasable upon lateral movement of said second wall in the plane thereof, a third wall removably positioned adjacent the first wall and overlapping the second wall to hold the latter against lateral movement, means for locking the third and first walls together and releasable only upon lateral movement of said third wall in the plane thereof, and a manually releasable catch for holding said third wall against lateral movement.
